[57] **ABSTRACT**

A bidirectional data transmission system for transmitting information between two terminal stations incorporating in each terminal station an arrangement for checking the received data and providing error correction when errors are detected in the received data. Each of the terminals include a memory for storing the m last words transmitted from that terminal. When an error is detected in one terminal, the transfer of received data to a data processor is blocked and a repetition request word is generated and transmitted to the other terminal. The other terminal detects the presence of the repetition request word in the received data and transmits a repetition start word and the last m data words stored in the memory to said one terminal to accomplish the error correction.

BIDIRECTIONAL DATA TRANSMISSION SYSTEM WITH ERROR CORRECTION

BACKGROUND OF THE INVENTION

The present invention relates to a bidirectional data transmission system for transmitting information between two terminal stations and more particularly to such a transmission system incorporating in each terminal station an arrangement for checking the received data and providing error correction when errors are detected in the received data.

SUMMARY OF THE INVENTION

In order to carry out the checking in accordance with the principles of this invention, n_2 parity digits are added to each group of n_1 digits or "word," and these words of $n=n_1+n_2$ digits or "Chr" words are transmitted while retaining in a memory MR the m last transmitted words.

The Chr words are of several types and distinction is made between:

The information words Ccr constituted by the data to be transmitted,

The repetition words Crd and Crs used in case of error of transmission, and

The synchronization words Csy transmitted in the absence of any other words.

In the receiving terminal—terminal TB for instance—if one or several errors are detected in a received word—the word (Chr) j for instance—the transfer of the received words to the data processing unit associated to said terminal is blocked. In addition, a "repetition request" word Crd is sent to terminal TA and, simultaneously, an alarm counter and a repetition counter are activated in terminal TB, and they both advance by one position at each word time.

When this word Crd is decoded in terminal TA, the normal transmission of the words is stopped, and a "repetition start" word Crs is sent and is followed by the contents of memory MR. When this word Crs is decoded in terminal TB, the advance of the alarm counter is stopped. At the following word times, the m repeated words are successively received and the repetition counter delivers a signal indicating the end of repetition at the m th word time which follows the time of detection of the erroneous word, said m th word time corresponding to the time of reception of the repeated word (Chr) j . At the next word time, at which the repeated word (Chr) j is received, the transfer of the words to the data processing unit is once again authorized and normal operation is resumed.

Therefore, an object of the present invention is to provide a bidirectional data transmission system in which the errors detected on reception are corrected by repetition.

A feature of this invention is the provision of a bidirectional data transmission system including two terminal stations in bidirectional communication with each other having error correction capability comprising first means disposed in each of the stations to process data words before transmission and after reception; second means disposed in at least one of the stations to store the last m data words transmitted, where m is an integer greater than one; third means disposed in at least the other of the stations to receive the data words from the one of the stations and to detect errors in the received data words; fourth means disposed in at least the other of the stations coupled to the third means and the first means responsive to a detected error in the received data words to block the received data words from the first means and to provide for transmission to the one of the stations a repetition request word; and fifth means disposed in at least the one of the stations coupled to the second means responsive to the repetition request word received from the other of the stations to provide for transmission to the other of the stations for error correction therein a repetition start word and the last m data words.

Another feature of this invention is the provision of the third means and the fourth means also being disposed in the

one of the stations and the second means and the fifth means also being disposed in the other of the stations to provide error correction capability for the other direction of data transmission.

Still another feature of the invention is the provision of means for controlling, when an error has been detected in terminal TB (TA) in an information word Ccr, the blocking of the data transfer to a data processing unit QP-B, and means for transmitting repetition request word Crd and for starting a repetition counter KC and an alarm counter KA which advance by one position at each word time.

A further feature of the invention is the provision of, in each terminal, means for storing the m last-transmitted words in a memory MR and means for controlling, at the reception of a word Crd, the transmission of a repetition start word Crs followed by the m words stored in memory MR.

Still a further feature of the invention is the provision of, in terminal TB (TA), means for generating a signal Rs at the reception of a word Crs, means for controlling, with this signal Rs, the blocking of the advance of counter KA which thus measures the time interval between the detection of the error and the reception of the repeated words, means for transmitting an alarm signal when said counter KA is not blocked after a time interval of $(k-1)$ word times, and means for unblocking the transfer of data to the unit QP-B when the counter KC, which measures the time interval between the last words which was correctly received and the reception—in repetition—of the word which was erroneous, reaches a position characterizing the m th word time after the error detection.

BRIEF DESCRIPTION OF THE DRAWING

The above-mentioned and other features and objects of this invention will become more apparent by reference to the following description taken in conjunction with the accompanying drawings, in which:

FIG. 1 is a general block diagram of the data transmission system according to the principles of the present invention;

FIG. 2 is a detailed block diagram of a reception clock CR; FIG. 3.a to 3.g are waveforms of signals in the circuit CR of FIG. 2;

FIG. 4 is a detailed block diagram of the reception time control RQ;

FIG. 5 is a detailed diagram of the transmission time control circuit SQ;

FIG. 6 is a detailed block diagram of the word analyzer WZ;

FIGS. 7.a to 7.k are waveforms of signals related to the operation of the data transmission system of the present invention when an error is detected in terminal TB;

FIGS. 8.b to 8.g are waveforms of signals related to the operation of the data transmission system of the present invention where an error is detected in terminal TA;

FIG. 9 is a general block diagram of the reception unit RL and of the transmission unit SL;

FIG. 10 is a detailed block diagram of the parity check circuit PY;

FIG. 11 is a detailed block diagram of the error detection circuit ED;

FIG. 12 is a detailed block diagram of the priority circuit PL; and

FIG. 13 is a detailed block diagram of the output logic circuit OL in circuit SL.

DESCRIPTION OF THE PREFERRED EMBODIMENT

In order to facilitate the description, the specification will be divided as follows:

1. Description of the System

1.1—General diagram (FIG. 1)

1.2—Time control circuits (FIGS. 2, 3, 4 and 5)

1.3—Word analyzer (FIG. 6)

2. Principle of Operation (FIGS. 7 and 8)

3. Receive Logic Circuitry (FIG. 9)

3.1—General outline

- 3.2—Parity circuit (FIG. 10)
 3.3—Error detection circuit (FIG. 11)
 3.4—Repetition control circuit

4. Transmit Logic Circuitry (FIG. 9)

- 4.1—General outline

4.2—Priority circuit (FIG. 12)

4.3—Input and output logic circuits (FIGS. 9 and 13).

It should be noted that in the detailed block diagrams the AND, OR, and EXCLUSIVE OR circuits do not carry any reference character, since they are defined without any ambiguity by the signals applied to them and by the corresponding logic conditions grouped in the various tables.

It should be noted in addition that the identical components in the terminals TA and TB of the system of FIG. 1 have the same reference characters followed by a letter A or B. This letter identifies whether the component is in terminal TA or TB. Where the description is concerned with a component that can be in either terminal TA or TB, the letter A or B will be dropped, since the description is applicable to the component regardless of the terminal in which it is located.

1—Description of the System

1.1—General diagram

FIG. 1 illustrates the general block diagram of the data transmission system according to the principles of the present invention. This system assures the bidirectional transmission of data between the two data processing units QP-A and QP-B or between such a unit and a peripheral or input-output circuit associated to it.

The assembly of one data processing unit and the circuits controlling the transmission constitutes a terminal TA or TB.

These terminals, which are practically identical, are connected together by the transmission channels *Dab* and *Dba*. For each transmission channel, the signals are transmitted by a transmit modem DS and are received by a receive modem DR. As is well known, these modems DS and DR control the conversion, in the two directions of transmission, of PCM (pulse code modulation) signals into modulated signals by a process such that the transmission over the lines *Dab* and *Dba* is optimized with regard to the transmission speed and the quality. The above-mentioned PCM signals are delivered by the units QP and by the circuits which are associated with them. By way of an example, the modulation process may be that known as "frequency shift modulation."

In each terminal, the information to be transmitted, supplied by data processing unit QP, is stored in register SR of transmit logic circuitry SL. In this circuitry, the information is processed; sent to the transmit modem DS and transmitted towards the other terminal.

The words received in a terminal are transferred, after decoding in the receiver modem DR, to register RR of receive logic circuitry RL. These words are applied to word analyzer WZ which delivers signals identifying the type of word which has been received.

A word comprises 10 digits *b*1, *b*2 . . . *b*10, wherein *b*9, and *b*10 are parity digits. The different types of words are presented in Table 1.

TABLE 1
 Types of words Chr

Reference	Priority level	Type of word	Signal delivered by decoder
<i>Crd</i>	1	Repetition request	<i>Rd'</i>
<i>Crs</i>	2	Repetition start	<i>Rs'</i>
<i>Cer</i>	3	Data	<i>Cr'</i>
<i>Csy</i>	4	Synchronization	<i>Sy'</i>

Thus, distinction is made between:

a. The normal words: these are the data words *Ccr* and the synchronization words *Csy*, these latter being transmitted by modem DS when the terminal has not other type of word to transmit; and

b. The repetition words: The parity digits of the transmitted words enable the detection of transmission errors, and each time an error is detected in a terminal—TA for instance—a repetition request word *Crd* is sent to terminal TB. At the

reception of this word, terminal TB retransmits the eight last transmitted words which are stored in a special memory contained in circuitry SL, this retransmission being preceded by a repetition start word *Crd* which indicates to terminal TA that it will receive repeated information.

In a given terminal, the data words delivered by unit QP are transmitted towards the other terminal only if:

a word *Crd* has not just been received, and

a word *Crd* must not be sent.

Thus, it is seen that a repetition has priority over the normal transfer of information.

As indicated in Table 1, the word *Csy* has the lowest priority level. However, the speed of transmission is chosen in such a way as to assure a frequent enough transmission of these words which are used for the synchronization of the received clocks in the terminals. A word *Csy* is characterized by the fact that it is alternating between binary 0 and binary 1, i.e., that it furnishes a maximum number of transitions, this being, as is well known, the optimum condition for obtaining a good synchronization.

This synchronization to the digits of the code *Csy* is carried out in receive modem DR and its description is beyond the scope of the present invention. Nevertheless, it should be noted that the signal *Sy* delivered by analyzer WZ is applied to receive clock CR for controlling the time position of the digit signals in such a way that a signal *R1*, for instance, appears exactly at the time of receiving the first digit of a word.

In the data transmission system according to the present invention, terminal TA includes transmit clock CS which defines the word times for transmission and terminal TB includes receive clock CR-B synchronized to the received signals. This same clock CR is used for transmission from terminal TB towards terminal TA, but terminal TA includes receive clock CR-A which generate word time signals delayed with respect to those generated by clock CS by a duration equal to the round trip transmission time between terminals TA and TB plus the data processing time in terminal TB.

Thus, the word time signals used for the reception and the transmission are in phase only in terminal TB. Nevertheless, it will be seen in the course of the description, that the circuits RL, SL and WZ are controlled in each terminal by the same digit time slot signals. Therefore, digit time slot signals delivered by clocks CR-A, CR-B and CS will bear the same references *T1*, *T2* . . . *T10*. All of these 10 signals define one word time.

1.2—Time control circuits

The clocks CR and CS will be described with reference to FIG. 2 which illustrates a block diagram of one clock CR and FIGS. 3.a to 3.g which illustrate the waveform of signals related to both clocks CR.

A clock CR receives the following signals:

Signal *Sy* (FIG. 3.a) obtained by decoding a word *Csy* in word analyzer WZ;

Signal *HR* (FIG. 3.b) which is the digit time slot signal generated in modem DR by the synchronization means mentioned above. The frequency of this signal defines the bit rate over the lines *Dab*, *Dba* and it will be assumed equal, for instance, to 2,400 bauds.

Signal *H1* (FIG. 3.c) which is a signal of very high frequency *F1* delivered by a pulse generator (not shown). Assume that *F1*=2.5 MHz. (megahertz) so that each signal *HR* of duty cycle 0.5 corresponds to the transmission of 520 signals *H1*.

Signal *Cd* which is delivered by modem DR and which characterizes the fact that a carrier frequency is received over the associated one of lines *Dba* and *Dab*.

Clock CR-B comprises:

Selector KM including a binary counter and timing signal decoder advances at the rate of the signals *H1* for the logical condition *HR-H1'm13* and defines 14 time positions *m1*, *m2* . . . *m14*. Its advance occurs under the control of the signals *HR* and it is blocked when it reaches the position *m13* so that the signals of fine timing signals it delivers are grouped at the beginning of the signal *HR* (FIG. 3.d). The signal *m1* defines the beginning of a digit time slot. It will be noted that the

signals $m1, m2 \dots m13$ occupy but a very small part of a digit time slot;

Selector KT including a binary counter and timing signal decoder and defines 10 time positions T1, T2 ... T10 defining the 10 digit time slots of a word. This selector advances by one position at each time $m1$ for the logical condition $Cd \cdot \bar{Sy} \cdot m1$ and it is forced into position T1 for the condition $Sy \cdot m1$, i.e., when a code Csy has been received. FIGS. 3.e, 3.f and 3.g illustrate the time positions of the signals T1, T2, T3; and

The receive time control circuit RQ and the transmit time control circuit SQ which deliver the time control signals used for receiving and transmitting.

FIGS. 4 and 5 illustrate the detailed block diagram of circuits RQ and SQ, respectively, and the logical conditions set up in these circuits are presented in Tables 2 and 3, respectively, wherein the expression (T1-T8), for example, symbolize the logical condition $T1+T2+\dots+T8$.

It will be noted that the signals A, B, D, E, F applied to the circuit SQ (FIG. 5) are delivered by priority circuit PL which will be described in paragraph 4.2 with respect to FIG. 9.

Clock CR-A comprises the same elements as clock CR-B with the exception of the transmit time control circuit SQ which is controlled by transmit clock CS.

The selectors of clock CS are the same as those shown in FIG. 2, but their control signals are different as follows:

TABLE 2

Signal	Condition
R2	$m2$
R3	$(T1-T8) \cdot m4$
R4	$T9 \cdot m4$
R5	$T10 \cdot m4$
R6	$T10 \cdot m5$
R7	$T10 \cdot m6$
R8	$T10 \cdot m7$

TABLE 3

Signal	Condition
S2	$T1 \cdot m3$
S3	$T1 \cdot m3$
S4	$(T1-T8) \cdot G \cdot m4$
S5	$(T1-T10) \cdot D \cdot m4$
S6	$B \cdot m5$
S7	$(T2-T8) \cdot G \cdot m2$
S8	$T9 \cdot G \cdot m4$
S9	$T10 \cdot G \cdot m4$
S10	$T10 \cdot m6$

$$G = A + B + E + F$$

a. For selector KM: The advance condition is: $HS \cdot H1 \cdot \bar{m13}$, the signal HS being the digit time slot signal generated in the modem DS and used to control the transmission over line Dab ; and

b. For selector KT: The signals Sy and $\bar{Sy}$ are not used to control it. In fact, the advance condition is $Cd \cdot m1$ and there is no forcing condition in T1.

1.3—Word analyzer

FIG. 6 illustrates the detailed block diagram of the word analyzer WZ (FIG. 1) which delivers, to the blocks RL and SL (FIGS. 1 and 9), the different orders to be carried out according to the type of word stored in the register RR (see Table 1). Table 4 presents the different logical conditions set up in this circuit and the meaning of the different orders.

The signals Es and $\bar{Es}$ which control the generation of these orders are supplied by error detection circuit ED located in circuitry RL which will be described in paragraph 3.3. It will only be noted that a signal Es appears as soon as an error is detected at the reception and that it is present up to the reception of the eight words sent in repetition by the distant terminal (the seven words which precede the erroneous word plus this word).

TABLE 4
Word analyzer WZ

Logical conditions	Meaning
$Sy \cdot \bar{Es} \cdot R7 \rightarrow Sy$ $t2 \rightarrow Sy$	Beginning of a word time.
$Sy' \cdot Es \cdot R7 = Rs$ $Rs' \cdot Rd' \cdot Es \cdot R5 = Cs$	Beginning of the reception of a repetition. Advance order for the word counter KC.
$Rd' \cdot \bar{Es} \cdot R7 = Rd$ $Rd' \cdot Es \cdot R5 = As$	Local repetition order. Advance order for the alarm counter KA.
$Cr' \cdot Es \cdot R7 = Cr$	Order for sending a word Cer to the unit QP.

It will be noted that the orders Cs and As are applied to the counters which control the reception of repeated information. The operation of these counter will be described in paragraph 3.4.

5 2—Principle of Operation

FIGS. 7.a to 7.k illustrate several waveforms of signals related to the operation of the data transmission system according to the present invention.

FIG. 7.b illustrates the word times reserved for transmission by unit SL-A of the words 1, 2, 3 etc. FIG. 7.d illustrates the word times reserved for the reception of these words by unit RL-B. These word times bear the same reference as in FIG. 7.b, but they are delayed, by way of example, by 0.75 word time in order to take into account the time of propagation between the two terminals TA and TB.

As it has been seen hereabove, the transmission word times in terminal TB are synchronized by the received word times and they are used for the transmission of the words 11, 12, 13 etc., towards the terminal TA (FIG. 7.e). On the other hand, in terminal TA, the received word times (FIG. 7.c) are not in synchronism with the transmission word times (FIG. 7.b).

Under normal operation, the words received in serial form in one terminal (TB, for instance) are transmitted in parallel form, at the end of a word time, to the unit QP-B (FIG. 7.k); this transfer being carried out under the control of a signal Cr (FIG. 7.j).

The operation of the data system will now be described in the case where an erroneous word is received in the terminal TB. To this end, it shall be assumed that the words 1 to 4 transmitted by terminal TA are normally received in terminal TB (FIG. 7.d), but that the checking of the word 5 has shown that it was affected by one or several errors.

An error detection circuit located in the unit RL-B delivers then a signal Es (FIG. 7.f) and a signal Rr . This error detection controls the following operations:

Suppression of the signal Cr (FIG. 7.j) so that the word 5 and the following words are not sent to the unit QP-B;

Clearing of word counter KC (FIG. 7.g) giving a signal Rf (FIG. 7.h); and

Clearing of alarm counter KA (FIG. 7.i).

During the time that terminal TB is receiving words 1 to 5, terminal TB transmits to terminal TA the words 11 to 15 (FIG. 7.e). At the next word time, the normal transmission is blocked and the signal Rr controls the sending of the repetition request word Crd . The words 16, 17 etc. . . are then transmitted normally.

In terminal TA, this word Crd is received after the word 15 (FIG. 7.c) and it is sent to word analyzer WZ-A which delivers a signal Rd which is transmitted to transmit logic circuitry SL-A. It is seen (FIG. 7.b) that this signal is received during the time of transmission of the word 8 which is normally transmitted as well as the preceding words 1, 2 . . . 7. At the next word time, the signal Rd controls the transmission to terminal TB of a repetition start word Crs followed by the eight preceding words 1 to 8 which were kept in a memory constituted by a shift register having a capacity of 80 digits.

This word is received in terminal TB at the time following the reception of the word 8 (FIG. 7.d) and word analyzer WZ-B delivers a signal Rs at the end of this time.

From the time of occurrence of the signal Es , counters KA and KC receive an advance signal at each word time so that they are (FIGS. 7.g and 7.i) in position 3 when the signal Rs appears. This signal blocks the advance of counter KC and controls the setting of counter KA to the position 7.

At the following word times, terminal B receives the repeated words 1, 2 . . . 8 (FIG. 7.d) and counter KC advances again normally after having been blocked during two successive word times in the position 3 (FIG. 7.g).

By comparing FIGS. 7.d and 7.g, it is seen that this counter reaches the position 7 at the word time 5 during which terminal TB receives the repetition of the word which had been detected as erroneous. Counter KC delivers then a signal Rf (FIG. 7.h) which controls the following operations:

Blocking of counter KC in position 7 (FIG. 7.g);

Suppression of the signal Es (FIG. 7.f); and

Generation of the signal C_r (FIG. 7.j) so that the word 5 and the following words are transmitted to the unit QP-B.

It has been seen previously that the detection of an error controlled the advance of alarm counter KA (FIG. 7.i). If the word C_{rs} is received within its normal delay which is, according to the diagrams of FIGS. 7.b to 7.e, 3 word times, the advance of counter KA is blocked and it is set in position 7 by the signal R_s . On the other hand, if this word C_{rs} is not received before counter KA is in position 6, a signal Ad appears which triggers an alarm in terminal TB.

To sum up, when an error has been detected in terminal TB, the signals E_s (FIG. 7.f), R_f (FIG. 7.h) and C_r (FIG. 7.j) define the time during which the transmission of signals to unit QP-B is stopped and the time TW (FIG. 7.k) is the waiting time for unit QP-B between the reception of the word 4 and the reception of the word 5 which has been detected as erroneous.

In terminal TA, the time of transmission of the eight received words is defined by a signal Do (FIG. 7.a).

FIGS. 8.b to 8.g concern the case where an erroneous word has been received in terminal TA, the word number 5 being assumed to be in error, by way of an example, as in the preceding case. It can be seen that in this case, where the word times are synchronous in RL-B AND SL-B, the word C_{rs} is sent at the word time which follows immediately the reception of the code C_{rd} (FIGS. 8.b and 8.c).

3—Receive logic circuitry

3.1—General Outline—

As it has been seen in the preceding paragraph, receive logic circuitry RL, which is shown in the upper part of FIG. 9, performs the following functions:

- Checking of the words received by means of parity check circuit PY and error detection circuit ED;
- Transfer to unit QP of the information C_{cr} which are recognized as correct;
- Transfer to transmit logic circuitry SL of an order R_r (order for transmitting a repetition request word C_{rd}) when an error has been detected; and
- Repetition check by means of circuit RC.

These functions are performed in the following circuits:

Input shift register RR which is a 10-digit shift register receiving the codes supplied by modem DR (FIG. 1) on the input D_r . The transfer of the codes is controlled by the signal R_2 ;

Parity computing circuit PY which will be described in detail in relation with FIG. 10 which delivers the calculated value of the parity digits b_9 and b_{10} on its output P_c ;

Error detection circuit ED which receives the calculated parity digits P_c and the parity digits P_r of the received code which are supplied by register RR. When the digits P_c and P_r are different, this circuit delivers, at the end of the word time, a signal R_y which is applied to circuitry SL as well as an error signal E_s which is applied to word analyzer WZ (FIG. 6, Table 4); and

Repetition control circuit RC which delivers, first, a signal R_f as long as the reception of the words is normal and the equipment is not in the repetition mode and, second, a signal Ad if a word C_{rs} has not been received with the normal delay after the transmission of a word C_{rd} .

3.2—Parity computing circuit

FIG. 10 illustrates parity computing circuit PY which is placed in each of the transmit and receive logic circuits and which computes the values of the parity digits b_9 and b_{10} .

As it has been seen previously, each word comprises:

Eight information digits $b_1, b_2 \dots b_8$, occupying the time positions $T_1, T_2 \dots T_8$; and

Two parity digits b_9 and b_{10} occupying the time positions T_9 and T_{10} .

The following rules are chosen for determining the value of these parity digits:

- The first parity digit b_9 gives the normal parity of the digits b_1 to b_8 , its value being chosen equal to 1 if this number comprises an even number of 1 and equal to 0 in the opposite case; and
- The second parity digit b_{10} gives the parity of the odd rank digits b_1, b_3, b_5, b_7 and b_9 .

This computed parity 2-digit code may present four different values of which only one is correct and it will be shown that it enables detection without any ambiguity, of errors in three consecutive digits.

5 If, for a given code, the parity code transmitted is 10:

A transmission error in an odd rank digit, such as b_1 , modifies the value of the digits b_9 and b_{10} and the computed parity code 01;

10 An in the digits b_1 and b_2 does not modify b_9 , but modifies b_{10} and the computed parity code is 11;

An error in the digits b_1, b_2 and b_3 modifies b_9 , but does not modify b_{10} and the computed parity code is 00.

This detection of consecutive errors is very important in a data transmission system wherein the errors occur generally in bursts.

15 In addition, the computed parity code 00 is obtained for one single error in an even rank digit.

The operation of circuit PY will now be described.

20 At the end of a word time, in T_{10-m7} , flip-flops B9 (which gives the value of the parity digit b_9), B10 (which gives the value of the parity digit b_{10}) and D (rank of the digits b_1 to b_9) are reset. It will be noted that all these flip-flops operate as scale-of-two's, this being symbolized by the signals applied symmetrically, such as the signal $m1$ applied to the flip-flop D.

25 It is thus seen that this flip-flop, which receives one signal at each word time, is in the 1 state for the odd digits $b_1, b_3 \dots b_9$.

During the time interval T_1-T_8 , the signals supplied by register RR (or SR) are applied to flip-flop B9, the final state of

30 which gives the value, $\bar{B}_9$ or B_9 , of the first parity digit b_9 , through the AND performing the logic function $RR \cdot (T_1-T_8) \cdot m4$. At the same time, an advance signal is applied to flip-flop B10 at each odd word time (logical condition: $D \cdot (T_1-T_8) \cdot m4$). In addition, if the digit b_9 is 1, an additional advance signal is applied to flip-flop B10 in T_9 (logical condition: $B_9 \cdot T_9 \cdot 4$).

35 As it may be seen by consulting Tables 2 and 3, the different time control signals used for the calculation of the parity are:

the signals R_3, R_4 and R_8 in receive logic circuitry RL; and the signals S_4, S_8 and S_{10} in transmit logic circuitry SL.

3.3 - Error detection circuit

40 FIG. 11 illustrates error detection circuit ED and Table 5 presents the different logical conditions. This circuit is controlled by certain signals of receive time control circuit RQ (FIG. 4) and there is shown in FIG. 11, between brackets and near these signals, the fine times at which they appear. There also is shown between brackets

$Cs = \bar{R}_s \cdot \bar{R}_d \cdot Es \cdot T_{10-m4} = \bar{R}_s \cdot \bar{R}_d \cdot Es \cdot R_5$ R_f	Advance signal for counter KC. Introduction of the number 7 in KC.
$As = \bar{R}_d \cdot Es \cdot T_{10-m4} = \bar{R}_d \cdot Es \cdot R_5$ Ad	Advance signal for counter KA. Introduction of the number 6 in K.

70 the fine times at which a flip-flop sets in the state which has been ordered by assuming a switching delay in one fine time.

In Table 5, the logical condition $B_9 \cdot Y_9$ is equivalent to the condition: $B_9 \cdot \bar{Y}_9 + B_{10} \cdot Y_9$ (EXCLUSIVE OR function).

75 In Table 5, it should be noted that:

- the signal S_q is an error signal supplied by modem DR (FIG. 1) when the quality of the received signals is estimated insufficient;

b. the signal R_f supplied by counter KC (FIG. 9) when the counter shows the number 7 which characterizes, as has been seen previously with respect to FIGS. 7.f to 7.h, a normal reception without any error;

the signal E_r means that an error has just been detected in the received word (flip-flop E_r in the 1 state);

d. the signal R_r is sent to transmit logic circuit SL (FIG. 9) for controlling the transmission of a word C_{rd} , repetition request; and

e. the error signal E_s is present up to the occurrence of a signal R_f : the condition E_s is thus present from the detection of error up to the end of the repetition.

3.4—Repetition control circuit

Circuit RC is shown in detail in the upper part of FIG. 9 and its logical conditions are presented in Table 6. It comprises alarm counter KA and repetition counter KC which are cleared by the signal R_r (Table 5) indicating the detection of an error.

Counter KA, which measures the time interval between the detection of an error and the reception of the word C_{rs} (repetition start), comprises four flip-flops and it receives, as advance signals, the signals A_s , supplied by word analyzer WZ, appearing at each word time when an error signal E_s is present. When a word C_{rs} is received, the signal R_s , supplied by word analyzer WZ, controls the setting of KA into position 7. After this operation, the signals A_s control its advance to the positions 8, 9 etc., (see FIG. 7.i).

If this word C_{rs} is not received before counter KA has reached the position 6, an alarm signal A_d appears, meaning that there is an important disturbance on the line or a cutoff.

When the transmission is resumed, a starting signal F_s is applied to the counter to set it in position 7 in order to suppress the signal A_d .

Repetition counter KC, which measures the time interval between the detection of an erroneous word and its repeated reception, comprises three flip-flops and it receives, as advance signals, the signals C_s , supplied by circuit WZ, at each word time for which an error signal E_s is present. It will be noted that the condition R_s blocks its advance at the time of reception of the word C_{rs} (see FIG. 7.g and generation of C_s in FIG. 6).

Last, it will be noted that the advance of both counters is blocked, in terminal TB, for instance, for the condition R_d (see generation of A_s and C_s in FIG. 6) so that there is not taken into account, in the measurement of the time intervals, the word time at which a repetition request has been received due to an error detected in the transmission over the line D_{ba} (FIG. 1).

4—Transmit logic circuitry

4.1—General outline

Transmit logic circuitry SL shown at the lower part of FIG. 9 performs the following functions:

a. Choice of the type of word to be transmitted which is made in the priority circuit PL which sets up the priority levels indicated in Table 1;

b. Transfer, in register SR, of the word to be transmitted which is selected by the priority circuit;

c. Generation of the parity digits and transmission of the word; and

d. Transmission of the eight words stored in the memory MR, said transmission following the sending of a word C_{rs} .

Circuitry SL comprises the following circuits

Shift register SR wherein are stored the words to be transmitted by means of transmission modem DS;

Priority circuit PL which receives the signals D_s , R_r , and R_d and which supplies, first, the signals A, B, D, E, F, used for the control of transmit time control circuit SQ (Table

3) and, second, the signals A', B', E', F' used for controlling the selection of the type of word to be transmitted. This circuit will be described in paragraph 4.2;

Input logic circuitry IC in which is performed, under the control of the signals A', B', E', F', the selection of the words to be transmitted; Parity computing circuit PY identical to that described in paragraph 3.2; and

Output circuit OC comprising output logic circuitry OL and memory MR constituted by an eight word shift register wherein are stored the eight last words transmitted. These words are retransmitted when a repetition is requested.

The circuits IC and OC will be described in paragraph 4.3.

4.2—Priority circuit

Priority circuit PL is shown in detail in FIG. 12 and the logical conditions are presented in Table 7. Circuit PL receives the following signals:

The signal D_s supplied by unit QP when an information word C_{rr} is available for transmission;

The signal R_r supplied by error detector ED of the reception unit RL (Table 5) when an error has been detected and a repetition request word C_{rd} must be transmitted; and

The signal R_d supplied by analyzer WZ when a repetition request word has been received (Table 4) and a repetition start word C_{rs} must be transmitted followed by the eight words stored in memory MR.

These signals are stored in the input flip-flops bearing the same references and the priority is set up, at the beginning of the following word time, by the transfer—in $T1 \cdot m2$ (signal S2)—of one of these signals into the appropriate associated one or ones of priority flip-flops A, B, D, E, F.

As may be seen on Table 1, the priority of the types of words to be transmitted is set up as follows, starting with the highest level:

Repetition request word C_{rd} ,
Repetition start word C_{rs} ,
Information word C_{rr} ,
Synchronization word C_{sy} .

In $T1 \cdot m3$ (signal S3), one of the signals A', B', E', F' which controls, in circuit IC (FIG. 9), the selection of the type of words to be transmitted, is generated. At the next fine time, the input flip-flops are reset to the 0 state. Last, in $T10 \cdot m6$ (signal S10), the priority flip-flops receive a resetting signal. It is thus seen that the priority flip-flop which has been set to the 1 state in $T1 \cdot m2$ (signal S2) remains in this state up to $T10 \cdot m6$, so that the condition $G=A+B+E+F$ is present during all this time for controlling the generation of the signals S4, S7, S8 and S9 (FIG. 5 and Table 3).

When the logical condition $R_d \cdot R_r \cdot S2$ is satisfied, flip-flop Do is set to the 1 state at the same time as flip-flop B. This latter flip-flop controls through signal B' the sending of the code C_{rs} and flip-flop D remains in the 1 state during the time required for the transmission of the code C_{rs} and of the eight repeated words extracted from memory MR. This time interval is measured by the counter KD which is cleared at the time $T1 \cdot m3$ (signal B') of the word time reserved to the transmission of the word C_{rs} and which receives an advance signal D' at each time $T1 \cdot m3$ corresponding to the transmission of a repeated word. When counter KD is in position 8, at time $T1 \cdot m4$ of the last repeated word, it supplies a signal R_g which controls the setting flip-flop Do to the 0 state (condition Do) and the suppression of the signal D'.

4.3—Input and output logic circuits

As it has been seen hereabove, input logic circuit IC (FIG. 9)

TABLE 7
Priority circuit PL

Time	Logical conditions	Remarks
T1.m2...	$\begin{cases} Rr.S1 \rightarrow A \\ Rr.Rd.S2 \rightarrow B, Do \end{cases}$ $Ds, \overline{Rr}, \overline{Rd}, Do, S2 \rightarrow E$ $\overline{Rr}, \overline{Rd}, Ds, Do, S2 \rightarrow F$ $Do, \overline{A}, \overline{B}, = D$	Control of the transmission time control circuit SR (Table 3).
T1.m3...	$A, S3 = A'$ $B, S3 = B'$ $E, S3 = E'$ $F, S3 = F'$ $Do, \overline{A}, \overline{B}, S3 = D'$	Transfer of a repetition request word Crd in the register SR. Transfer of a repetition start word Crs in the register SR. Transfer of a word Ccr in the register SR. Transfer of a word Csy in the register SR.
T1.m4...	$A' \rightarrow \overline{Rr}$ $B' \rightarrow \overline{Rd}$ $E' \rightarrow Ds$	Command in T1.m3.
T10.m6...	$\{S10 \rightarrow \overline{A}, \overline{B}, \overline{E}, \overline{F},$ $\{S10, Rg \rightarrow Do$	

TABLE 8
Control conditions for the output flip-flop J

Data	Time available for storage	Control time
Sr-Sr	m3 to m2	S4 = (T1-T8). G.m4
B9-B9	T8.m5 to T10.m6	S8 = T9. G.m4
B10-B10	T9.m5 to T10.m6	S9 = T10. G.m4
Mr-Mr	m6 to m5	S6 = (T1-T10). D.4

controls the transfer, to the register ST, of the word to be transmitted, the selection being carried out under the control of one of the signals A', B40, E' or F' appearing at time S3-T1.3.

When priority circuit PL delivers a signal E' which can appear only if unit QR delivers a signal Ds meaning that a word Ccr is ready for transmission, said circuit PL controls the transfer of the word Ccr into register SR. When circuit PL delivers one of the selection signals A', B' or F', this signal is applied to word generator WG which transfers the requested word Crd, Crs or Csy into register SR. Such a word generator is well known and will not be described in detail.

FIG. 13 illustrates the detailed diagram of output circuit OC in which logic circuit OL comprises, first, AND circuits controlled by the signals S4, S5, S8, S9, second, two 4-input OR circuits represented by diodes with the outputs thereof being referenced Lg0 and Lg1 and, third, the flip-flop J controlled by outputs Lg0 and Lg1.

Circuitry OL receives the following signals:

Signals Sr or $\overline{Sr}$ which appear on the outputs 0 and 1 of the last stage of register SR (FIG. 9);

Signals B9 or $\overline{B9}$ and B10 which are delivered by parity circuit PY (FIG. 10); and

Signals Mr or $\overline{Mr}$ which appear on the outputs 0 and 1 of the last stage of memory MR.

Table 8 shows the conditions for the storage of the digits in the output flip-flop J which controls the coupling of the digits, first, to modern DS and, second, to the memory MR.

If one considers the information digits stored in register SR under the control of the signal S3=T1.m3, the first digit B1 is available from time T1.m4 on and it is stored in flip-flop J under the control of the signal S4. The signal S7 controls, at the following time m2, the advance by one position in register SR and the digit B2 is available from the time T2.m3 up to the time T3.m2 and it is stored in the flip-flop J in T2.m4, etc.

Last, the storage conditions of the parity digits B9 and B10 are deduced directly from Table 8.

While I have described above the principles of my invention in connection with specific apparatus, it is to be clearly understood that this description is made only by way of example, and not as a limitation to the scope of my invention as set forth in the objects thereof and in the accompanying claims.

We claim:

1. A bidirectional data transmission system including two terminal stations in bidirectional communication with each other having error correction capability comprising:

first means disposed in each of said stations to process data words before transmission and after reception;

second means disposed in at least one of said stations to store the last m data words transmitted, where m is an integer greater than one;

third means disposed in at least one of the other of said stations to receive said data words from said one of said stations and to detect errors in said received data words;

fourth means disposed in at least one of the other of said stations coupled to said third means and said first means responsive to a detected error in said received data words to block said received data words from said first means and to provide for transmission to said one of said stations a repetition request word; and

fifth means disposed in at least one of said stations coupled to said second means responsive to said repetition request word received from said one of the other of said stations to provide for transmission to said one of the other of said stations for error correction therein a repetition start word and said last m data words;

each of said data words, said repetition request words and said repetition start words including

n_1 information digits, where n_1 is an integer greater than one, and

n_2 parity digits, where n_2 is an integer greater than one; said third means including

a parity computing circuit responsive to said n_1 information digits to compute the parity thereof,

an error detection circuit coupled to said computing circuit responsive to said n_2 received parity digits and said computed parity to detect errors in said received words; and

a repetition control circuit including

a plural binary stage repetition counter, and

a plural binary stage alarm counter,

both of said counters advancing one count at each word time following the detection of an error.

2. A system according to claim 1, wherein said one of said stations also includes said third means and said fourth means and said other of said stations also includes said second means and said fifth means to provide error correction capability for the other direction of data transmission.

3. A system according to claim 1, further including a first clock disposed in said one of said stations to control the transmission of words therefrom; a second clock disposed in said other of said stations synchronous with said first clock to control the transmission of words therefrom; and

a third clock disposed in said one of said stations to control the reception of words therefrom, the timing signals of said third clock being identical to the timing signals of said first clock, but delayed with respect thereto an amount corresponding to the round trip propagation time between said stations plus the data processing time of said other of said stations.

4. A system according to claim 1, further including means to provide synchronizing words, and means to provide said synchronizing words for transmission in the absence of said data words, said repetition request words, and said repetition start words.

5. A system according to claim 1, wherein said fourth means includes

sixth means responsive to said received words to distinguish between said data words and said repetition start words,
 seventh means coupled to said sixth means and said third means responsive to said detected error and an output signal from said sixth means to provide said repetition request word for transmission, and
 eighth means coupled to said sixth means and said third means responsive to another output signal from said sixth means to block said received data words from said first means.

6. A system according to claim 1, wherein said fifth means includes

sixth means responsive to said received words to distinguish between said data words and said repetition request words, and
 seventh means coupled to said sixth means and said second means to provide for transmission of said repetition start word and said last m data words.

7. A system according to claim 1, wherein said fourth means includes

sixth means responsive to said received words to distinguish between said data words and said repetition start words and produce a plurality of output signals,
 seventh means to said third and sixth means responsive to said detected error and one of said plurality of output signals to provide said repetition request word for transmission, and

- 30 -

eighth means coupled to said sixth means and said third means responsive to a second one of said plurality of output signals to block said received data words from said first means;

said third means includes

a parity computing circuit responsive to said $n1$ information digits to compute the parity thereof.

an error detection circuit coupled to said computing circuit responsive to said $n2$ received parity digits and said computed parity to detect errors in said received words,

a repetition counter coupled to said detection circuit and said sixth means responsive to a detected error and a third one of said plurality of output signals to advance one count at each word time following the detection of an error, and

an alarm counter coupled to said detection circuit and said sixth means responsive to a detected error and fourth and fifth ones of said plurality of output signals to advance one count at each word time following the detection of an error; and

said fifth means includes

ninth means responsive to said received words to distinguish between said data words and said repetition request words, and

tenth means coupled to said ninth means and said second means to provide for transmission of said repetition start word and said last m data words.
